UNITED STATES PATENT OFFICE

2,674,000

TOOTHBRUSH HAVING DENTIFRICE
FEEDING MEANSJohn J. McDonald, Jr., and Henry J. Gruthusen,
Chicago, Ill.

Application November 9, 1949, Serial No. 126,362

1 Claim. (Cl. 15—137)

1

Our invention relates to improvements in a combined brush and dispenser for dispensing and using powder or paste.

Our invention relates more particularly to a device of the character described especially adapted for use in dispensing and using toothpaste, toothpowder or similar materials.

The principal object of the present invention is to provide a container and brush for use in brushing teeth, a device which is so constructed that the powder or paste to be spread over the teeth is carried in the handle of the brush.

A further object of the invention is to provide a device of the type described wherein means are provided at the end of the handle for forcing a supply of powder or paste to the face of the brush whenever desired.

A further object of the invention is to provide a device of the type described, wherein the handle is so arranged that the end can be removed for easy access to the interior for filling or cleaning the same.

A further object of the invention is to provide a device of the type described that is easily and simply constructed and one which will not become broken or inoperative in spite of long and hard usage.

Other objects and advantages will be more apparent from the following description wherein reference is had to the accompanying drawings upon which:

Fig. 1 is a plan view of my improved toothbrush construction;

Fig. 2 is a longitudinal cross-sectional view thereof taken on the line 2—2 of Fig. 1;

Fig. 3 is an enlarged transverse sectional view taken on the line 3—3 of Fig. 2;

Fig. 4 is an end view of the same; and

Fig. 5 is a modified cross-sectional view similar to Fig. 2; and showing changes in construction.

In the embodiment of the invention which we have chosen to illustrate and describe, the same may generally comprise a hollow housing member 10, a block 12 within which toothbrush bristles may be mounted, a plug 14 for the end of the hollow housing 10, and a plunger member 16.

The housing 10 may be generally cylindrical in shape as shown, and in one form of construction is adapted to be open at both ends, the forward end being closed by the plug 14, the opposite end providing an opening for the introduction of the movable plunger 16 by which toothpaste or powder is forced out through the bristle holder, as will presently be explained.

2

The block 12 may be generally rectangular as shown and capable of being seated in the slot 18 cut in the upper wall of the housing 10, the parts being secured in working operation by an adhesive or other support. The block 12 is provided with apertures to seat a plurality of groups of bristles B placed in rows upon one face of the same, the block also having a pair of drilled holes 22 which extend from the face of the same to the back so that the holes are in communication with the space in the housing 10.

The plunger 16 heretofore mentioned may have a generally cylindrical stem 24 and an enlarged head 26 so that when the plunger is inserted in the housing and pressed forward until the head reaches the end of the tube or housing 10, the foremost position of the plunger is thus reached.

From the above and foregoing description it can be seen that we have provided in a toothbrush and handle a construction wherein the handle may be used as a magazine for powder or toothpaste, the plunger 16 being provided so that as the material in the housing is used up, the same can be pushed forward until it reaches its limit stop. Paste, powder or other semi-plastic material may be placed in the hollow housing 10, the plunger inserted and the material in the housing can be extruded through the passageways 22 to the bristles for use.

In Fig. 5 we have shown a modified form of construction wherein the block 12 has been provided with the extension 12a so that the entire space in the housing 10 is filled from the openings 22 forward in the same. We have also modified the construction of the plunger 16 by extending the same as shown and with the reduced extension 16a adapted when the plunger is completely introduced to extend below the block 12 with the end engaging the portion 12a, thereby permitting the use of all of the toothpaste or other material that has been placed in the housing 10.

From the foregoing description it can be seen that the combined toothbrush and magazine for paste or other material is extremely simple in construction and operation, it being generally the purpose to construct the same of plastic or similar material that can be easily and cheaply molded or fabricated. Thus in its preferred construction, three or four parts are all that are required for the complete assembly, making the unit an especially cheap article to produce and manufacture.

While we have illustrated and described a spe-

cific embodiment of the invention and a modification thereof, it will be apparent to those skilled in the art that changes and modifications may be made in the exact details shown, and we do not wish to be limited in any particular; rather what we desire to secure and protect by Letters Patent of the United States is:

A dispenser for tooth paste comprising a hollow cylindrically shaped housing, a block mounted in the end of the same, said block having a shoulder extending forward in a horizontal plane in the upper part of said housing, bristles in the upper face of said block, said bristles extending in a lateral direction from said block and housing, said block having vertical passageways extending therethrough and communicating with the inside of said housing, and a cylindrical plunger member telescopically mounted in said housing and longitudinally movable therein to force paste through said passageways in said block, said plunger having an extension

capable of underlying the shoulder of said block and engage against the end of said block to extrude the paste in said housing.
